UNITED STATES PATENT OFFICE.

CYRUS H. LOUTREL, OF SOUTH ORANGE, NEW JERSEY, ASSIGNOR TO THE NATIONAL LOCK WASHER COMPANY, OF NEWARK, NEW JERSEY, A CORPORATION OF NEW JERSEY.

MACHINE FOR COILING METAL.

1,137,412.

Specification of Letters Patent.

Patented Apr. 27, 1915.

Application filed April 8, 1914. Serial No. 830,428.

To all whom it may concern:

Be it known that I, CYRUS H. LOUTREL, a citizen of the United States, residing at South Orange, Essex county, New Jersey, have invented certain new and useful Improvements in Machines for Coiling Metal; and I do declare the following to be a full, clear, and exact description of the invention, such as will enable others skilled in the art 10 to which it appertains to make and use the same.

My present invention pertains to an improved machine for coiling metal, the construction and advantages of which will be 15 hereinafter set forth, reference being had to the annexed drawings, wherein:

Figure 1 is a horizontal sectional view of the machine, the stock or metal being shown as being coiled upon the mandrel and the 20 primary or initial bending or coiling device as withdrawn; Fig. 2 a sectional elevation on the line 2—2 of Fig. 1; Fig. 3 a front elevation with the primary bending or coiling device in operative position; Fig. 4 a top 25 plan view, the primary coiling device being broken away and partly in section; Fig. 5 a vertical sectional view on the line 5—5 of Fig. 4; Fig. 6 a perspective view of the stationary die; Fig. 7 a detail sectional 30 plan, showing the relation of the primary coiler to the stock, mandrel and the stationary die; Figs. 8, 9 and 10 detail sectional views, illustrating the operation of the primary coiler; Fig. 11 a perspective view of 35 that end of the stock after it is primarily coiled; and Fig. 12 a sectional plan, on an enlarged scale over that of Fig. 1, illustrating the operation of the positively-driven roller dies or forming rolls.

The main object of the present invention 40 is to provide a simple and readily adjustable machine, wherein stock of various sizes may be accurately coiled, and this with a minimum expenditure of power and wear upon 45 the parts.

A further object of the invention resides 50 in the provision of means whereby the machine may be initially and quickly adjusted for stock of different sizes and coils having different diameters, associated with means whereby the pressure or forming rolls or dies may be retracted from or advanced to-

ward the mandrel independently of any change of position in the initial adjusting mechanism.

A still further object resides in the provision of simple means whereby the stock may be initially positioned about the mandrel prior to the final adjustment and operation of the forming rolls.

Another object of the invention is to provide means whereby the mandrel and its supporting member may be readily removed and another of different size substituted.

With these and other objects in view, a detailed description will be given, reference being made to the annexed drawings, wherein, 1 denotes the bed or base of the machine, upon the rear of which there is secured a standard 2, in which is journaled a driving 65 shaft 3 carrying a driving pinion 4, the outer end of the shaft being threaded for the reception of a chuck 5, adapted to receive and clamp a mandrel 6. A spider 7, secured to standard 2, forms an additional 70 support for the shaft 3. A series of stub shafts 8, three in the present instance, are journaled in standard 2 and each has secured to it a gear 9, which gears intermesh 75 with and are driven by gear 4.

The pressure forming dies or rolls, of which there are three, are designated by 10, and each is mounted upon a shaft 11, which at its rear end is connected through the medium of a gimbal joint 12 to the forward end 85 of a two-part telescopic shaft 13, which in turn is connected by a gimbal joint 14 with the forward end of shaft 8. Shafts 11 and rolls 10 are designed to be adjusted simultaneously toward and from the mandrel in 90 parallelism, and the supporting mechanism therefor is such that a wide range may be had by adjusting one device to secure the initial adjustment for different sized stock and different sized mandrels and coils, and 95 a second device whereby the rolls may be adjusted from and toward the mandrel when a new piece of stock is to be positioned upon the mandrel. The rear member of the supporting frame for such adjusting mechanism comprises a ring-shaped member 15 secured to bed 1 by lugs or brackets 16, the lower portion of said frame extending 100 downwardly through an opening 17 formed

in the bed 1. A similarly shaped member 18 is secured to the bed or table by brackets 19, adjacent the forward portion of the opening 17. Each of said members 15 and 18 is provided with a groove in its outer face, and serve to support, respectively, rotatable cam plates 20 and 21, plate 20 being held up to member 15 by clips 22, while plate 21 is held in place by clips or blocks 23.

10 Each of the cam plates 20 and 21 is provided with three cam grooves or ways 24 in which are mounted rollers or bushings 25, through which extend pintles or stub axles 26 of fulcrum blocks 27, arranged opposite each other in pairs. The heads 26^a of the stub axles afford a means whereby the blocks may be brought into clamped relation with the plates when the parts are adjusted, the inner ends of the axles being threaded into 20 the blocks. Each pair of blocks is connected by a cross-bar 28, and to each block there is pivoted a link 29, which in turn is connected to a second link 30, the latter in turn being likewise connected to the boxes 31, 31 in which the shafts 11 are mounted and turn. Said boxes 31, 31 and the blocks 27, 27 are mounted in radially disposed guide-ways 32, 33, formed respectively in the spoke-shaped members 34, 35 of the 30 fixed frame members 15 and 18. Cam plates 20 and 21 are connected to each other by means of a cross bar 36 and posts 37, the bar carrying a handle 38 by means of which the plates may be adjusted in unison.

35 Located intermediate frame members 15 and 18 and rotatably supported upon the latter by clips 39, is a cam ring 40, formed of two parts secured together, as shown in Fig. 1, and provided or formed with three 40 cam grooves 41, in each of which there is mounted a spool-shaped roller 42, the axle of which, see Fig. 5, passes through the outer end of an arm 43. Said arm passes through an opening formed in cross-bar 28 and at its inner end is pivotally connected to the overlapping ends of two links 44, 45, the outer ends of which are likewise connected to the links 29 and 30 at their points of connection. A handle 46 is secured to 50 the cam ring 40 by which the ring may be turned or adjusted. Through the manipulation of handle 38, the initial adjustment of the rolls 10 will be effected, that is to say, where a large mandrel is employed, or large 55 stock used, the shifting of the cam plates 20, 21 will move the fulcrum blocks 27 (in or out) and consequently shift the bearing boxes 31 accordingly.

60 The movement of the rolls toward the mandrel in their final adjustment into contact with the stock, or their removal therefrom to admit of the positioning of a new length of stock, is effected through handle 46, and the consequent movement of the

arms 43, an inward movement thereof tending to bring the links 29, 30 into alinement and an outward movement serving to throw them out of alinement and consequently moving the bearing blocks 31 outwardly. Mandrel 6 is preferably knurled upon its outer end, and is supported adjacent thereto by a spider frame 47 secured to the forward fixed frame member 18. Said spider frame is provided with a neck 48 which forms the support for a fixed guide or die 75 49, the outer end of which is formed with a spirally-inclined face 50 starting from the inner end of a shoulder 51. Rolls 10 are adjustably and removably secured upon their shafts and each is provided with a rolling 80 face 52, which bears directly upon the stock and forces the same against the mandrel, and likewise an upstanding flange 53, which takes against the forward face of the stock. The rolls, as will be noted, are arranged in 85 a stepped relation to each other, and lie close to the spirally-inclined face 50 of the fixed die 49, or in other words, the rolls lie in a spiral path which conforms to the spiral 90 face 50 of the die 49.

The stock to be coiled is designated by 54 and passes to the rolls and mandrel through a trough-shaped guide 55, adjustably secured to the fixed frame member 18 by a screw 56. At one side of the machine, in 95 line with said trough, there is mounted a combined guide and clamping member comprising a housing 57, in the upper wall of which there is mounted a clamping pin 58, adapted to be moved into clamping relation with the stock through the medium of a cam 59. A block 60, adapted to the size of the stock being operated upon, will be placed in the lower portion of the housing, as shown.

In use the stock 54 will be passed through the clamp, through the guide, and beneath the adjacent roll, the rolls at such time being retracted, as in Figs. 3 and 4, until the end of the stock extends slightly beyond the 100 mandrel; it is then bent or curved downwardly around the mandrel until it assumes the form shown in Fig. 11, after which the rolls will be moved inwardly into contact with the stock. This initial bending may be effected in any desired manner; in fact, the stock may be so bent before it is positioned. To facilitate this operation and to enable the stock to be so bent that it is unnecessary to 110 cut off the end of the formed coil owing to 115 improper formation which, of course, is a wastage, I preferably employ a manually-operated device for accurately and quickly forming the initial bend.

Upon the forward end of the table there 120 is mounted a sliding carriage 61, operable through a handled bell-crank lever 62 and a connecting link 63. A post or standard 64

extends upwardly from the carriage, in the upper bifurcated end of which is mounted a collar 65 through which and the standard there extends a sleeve 66. Said sleeve and 5 collar are secured together by a set-screw 67, and the sleeve forms a support for a shaft 68 which may be moved endwise therein. The shaft at its inner end carries a head 69, having a recess 70 therein, into which the 10 mandrel may pass, see Figs. 8 and 9, the head having a hook 71, adapted to engage the stock and coil the same around the mandrel as the shaft and head are rotated. Such rotation is effected through the agency of a 15 crank 72 and in order to effect an endwise movement of the shaft as it is rotated, a cam 73 is secured to the shaft 68, said cam taking against a stud 74, carried by the post or standard.

20 In the use of this device the stock is first positioned over the mandrel, as in Fig. 8, and the locking pin 58 is forced downwardly to hold the stock; then upon rotation of the head 69 by the crank 72 the hook engages 25 the stock and wipes it around the mandrel, cam 73 gradually retracting the head so as to give the bend a spiral twist, as in Fig. 11. When this is effected and the hook has ridden off the end of the stock the shaft 68 and 30 the allied parts are drawn outwardly away from the mandrel and the carriage is moved to the left, the clamp released and the rolls moved inwardly, through the manipulation of handle 46, into contact with the stock.

35 The operation is then entirely automatic, the mandrel rotating clockwise, while the forming rolls rotate in the opposite direction. Where stock of different sizes is used, an adjustment of the blocks 27 may be 40 readily effected through the operation of handle 38, moving said blocks inwardly or outwardly, as required, nuts 26^a being tightened after such adjustment, after which the rolls may be manipulated through the me- 45 dium of handle 46, to give that relatively slight movement which is necessary to effect adjustment when a new length of stock is positioned.

As will be readily appreciated, the ma- 50 chine may be so adjusted as to accommodate and operate upon stock of various sizes; so too, the diameter of the coil may be changed by substituting mandrels of different sizes, and again, the spread or distance between 55 the various convolutions may be determined and produced by substituting a die 49 having a different pitch to its spirally-disposed face, and adjusting the position of the rolls to correspond thereto.

60 Having thus described my invention, what I claim is:

1. In a coiling machine, the combination of a rotatable mandrel; a fixed die surround- 65 ing the same and having a spirally-inclined

face; a plurality of forming rolls located in 65 a spiral stepped relation with reference to said face; means for positively driving said rolls; means for effecting an initial adjustment of said rolls toward the mandrel; and means for moving said rolls into and out of 70 operative relation with the die and mandrel.

2. In a coiling machine, the combination of a rotatable mandrel; a fixed die surround- 75 ing the same and having a spirally-inclined working face; a plurality of shafts spaced about said mandrel; a roll carried by each shaft and adapted to coöperate with the die and mandrel; a plurality of pairs of ful- 80 crum blocks, one pair for each shaft; means for adjusting said blocks simultaneously to- ward and from the mandrel; bearing boxes for each shaft; connections between said boxes and blocks; means for simultaneously adjusting said connections, whereby the 85 shafts, and consequently the rolls, may be adjusted with reference to the mandrel and die; and means for driving the shafts, and consequently the rolls carried thereby.

3. In a coiling machine, the combination of a rotatable mandrel; a fixed die surround- 90 ing the same and having a spirally-inclined working face; a plurality of shafts spaced about said mandrel; a forming roll carried by each shaft adjacent the outer end of the mandrel and the working face afore- 95 said; means for rotating said shafts; a plu- 100 rality of pairs of fulcrum blocks, one pair for each shaft; a cam mechanism for simultaneously adjusting said blocks toward and from the mandrel; a pair of supporting boxes for each shaft; a link connection be- 105 tween the boxes and their respective fulcrum blocks; and a cam mechanism for simultane- 110 ously adjusting said link connections.

4. In a coiling machine, the combination of a rotatable shaft; a chuck carried thereby; a mandrel secured in said chuck; a fixed frame; a spider secured thereto and forming a support for the mandrel adjacent its outer end; a spirally-faced die carried by the 110 spider and surrounding the mandrel, the end of the mandrel projecting beyond said face; a plurality of shafts arranged around the mandrel; a forming roll carried by each shaft, the rolls standing in a stepped rela- 115 tion to each other and having their working faces lying close to the spiral face of the die; a pair of boxes for each shaft; a ful- 120 crum block for each box, said blocks being arranged in pairs and movable in radially-disposed ways in the fixed frame; a cam mechanism for simultaneously adjusting said blocks toward or from the mandrel; an adjustable link connection between each block and its adjacent box; a cam mecha- 125 nism for effecting a simultaneous adjustment of said link connections; and means for driving the shafts.

nism for effecting an initial, simultaneous adjustment of the rolls with reference to the mandrel according to the size of the stock to be coiled, whereby the rolls may be quickly 5 adjusted and likewise readily retracted from and returned to their adjusted position with reference to the mandrel.

In testimony whereof I affix my signature in presence of two witnesses.

CYRUS H. LOUTREL.
